UNITED STATES PATENT OFFICE.

DWIGHT SLATE, OF HARTFORD, CONNECTICUT.

IMPROVED APPARATUS FOR GRINDING CUTTER-BITS FOR RIFLING-MACHINES,

Specification forming part of Letters Patent No. 41,646, dated February 16, 1864.

To all whom it may concern:

Be it known that I, DWIGHT SLATE, of Hartford, in the county of Hartford and State of Connecticut, have invented a new and useful Tool for Shaping Rifling-Cutters; and I do hereby declare that the following is a full, clear, and exact description thereof, reference being had to the accompanying drawings, making part of this specification, and to the letters of reference marked thereon.

My invention relates to an apparatus for giving shape to the edges of the cutters which are used to rifle the barrels of fire arms.

Previous to my invention difficulty has been experienced in giving to the edges of the teeth of rifling-cutters the proper curvature for correctly shaping the bottoms of the grooves, and in rendering uniform the height and curvature of the edges of all the teeth where, as is usually the case, several cutters are used in the same rod, and each one cuts in all the grooves successively, in which case a slight variation in the height of the teeth causes an unequal action of the different cutters to an extent which is detrimental to the work.

It is the object of my invention to produce a tool by which the edges of the cutters' teeth may be evened and properly curved while they are in their places in the rifling-rod, or in a holder which has the precise form of the rod, and by which the several cutters may be rendered uniform in height and curvature.

To this end my said invention consists in the employment of a sleeve or equivalent guide so constructed that it may be applied to the rifling-rod and rotated about the axis of the rod in combination with a slab of oil-stone or other similar abrading substance, which is so attached to the said sleeve that the rotation of the sleeve will cause the edges of the rifling-cutters to be ground until they are of even height and perfectly concentric with the axis of the rod, substantially as hereinafter clearly described.

To enable others skilled in the arts to make and use my invention, I will proceed to a description thereof, referring to the accompanying drawings, in which—

Figure 1 represents a side elevation of the apparatus. Fig. 2 is an end elevation of the same. Fig. 3 is a longitudinal section of the tool,

shown in its application to a rifling-rod, parts of which are also shown in section; and Fig. 4 is a cross-section of the same.

Similar letters denote the same parts in the several figures, wherein—

a represents a long sleeve the bore of which fits the rifling-rod for which the instrument is to be used; and *b* is a radial arm, which is secured to *a* at about midway of its length. *c* is a slab of oil-stone, which is fastened to the face of the arm *b* by means of the clamp *d*. The lower part of the oil-stone slab *c* enters a hole which is made through the side of the sleeve *a*, and it is so adjusted that its extreme lower end will (when the sleeve is rotated about its axis) describe a circle equal in diameter to that of the curve which is proper for the cutters' teeth. The central part of the bore of the sleeve *a* is enlarged, thereby forming a chamber two or three times longer than the rifling-cutters. This chamber permits the protrusion of the cutters above the surface of the rifling-rod to which the sleeve may be applied. The end of the slab *c* enters the aforesaid chamber at the middle of its length.

In Figs. 3 and 4 there are shown parts of a rifling-rod of the usual construction, in which *s* is the shell; *r*, the inner rod, which is of conical shape at *m*, where the three cutters *n* are supported.

Having described the construction of my invention, I will proceed to describe the mode of applying it. The cutters *n* of the rifling-rod having been dropped below the surface of the shell *s*, the sleeve *a* of the grinding apparatus is slipped onto the shell until the oil-stone slab *c* is directly over the cutters, which are then thrust out by adjusting the cone *m* so far that the end of the slab *c* will rub on the edge of that tooth of the cutters which may be the highest. The sleeve *a* is then rotated rapidly by rolling it between the hands, and the cutters must be gradually forced out until the abrading action on the teeth by the piece of oil-stone *c* has ground off the edges of all the teeth to an equal height and the proper curvature. This action of the oil-stone removes all nicks and inequalities of the edges of the teeth and leaves them perfectly smooth, and in such shape that they may readily be sharpened in the usual way. When the end of the

slab *c* becomes worn away, it may be adjusted by loosening the clamp *d* and resetting the slab.

The slab *c* may be made of any material which has an abrading surface capable of grinding away the edges of the hardened cutters without crumbling them.

What I claim as my invention, and desire to secure by Letters Patent, is—

The oil-stone slab *c*, in combination with the

sleeve *a*, or their respective equivalents, constructed, arranged, and operating substantially in the manner hereinbefore set forth.

In testimony whereof I have hereunto set my hand this 18th day of August, 1863.

DWIGHT SLATE.

In presence of—

FRANCIS FELLOWES,

FRANCIS FELLOWES, Jr.
